CLAIM

The ornamental design for a sanding machine, as shown and described.

DESCRIPTION

FIG. 1 is a front perspective view of the sanding machine of the present invention;

FIG. 2 is a rear perspective view of the invention of FIG. 1;

FIG. 3 is a front elevational view of the invention of FIG. 1;

FIG. 4 is a rear elevational view of the invention of FIG. 1;

FIG. 5 is a top view of the invention of FIG. 1;

FIG. 6 is a bottom view of the invention of FIG. 1;

FIG. 7 is a left side elevational view of the invention of FIG. 1;

FIG. 8 is a right side elevational view of the invention of FIG. 1;

FIG. 9 is a front perspective view of the invention of FIG. 1, further comprising a plurality of rectangular voids provided in a base portion and in a central portion of the invention;

FIG. 10 is a rear perspective view of the invention of FIG. 9;

FIG. 11 is a front elevational view of the invention of FIG. 9;

FIG. 12 is a rear elevational view of the invention of FIG. 9;

FIG. 13 is a top view of the invention of FIG. 9;

FIG. 14 is a bottom view of the invention of FIG. 9;

FIG. 15 is a left side elevational view of the invention of FIG. 9;

FIG. 16 is a right side elevational view of the invention of FIG. 9;

FIG. 17 is a front perspective view of the invention of FIG. 9, further comprising on an upper portion of the invention visible portions of a circular platen and a ring-shaped region surrounding the platen;

FIG. 18 is a rear perspective view of the invention of FIG. 17;

FIG. 19 is a front elevational view of the invention of FIG. 17;

FIG. 20 is a rear elevational view of the invention of FIG. 17;

FIG. 21 is a top view of the invention of FIG. 17;
FIG. 22 is a bottom view of the invention of FIG. 17;
FIG. 23 is a left side elevational view of the invention of
FIG. 17; and,

FIG. 24 is a right side elevational view of the invention of
FIG. 17.
